UNITED STATES PATENT OFFICE.

HOUSTON LEE BROWN, OF ST. PAUL, VIRGINIA.

CLOTH-MEASURING MACHINE.

1,288,498.

Specification of Letters Patent. Patented Dec. 24, 1918.

Application filed October 26, 1917. Serial No. 198,690.

To all whom it may concern:

Be it known that I, HOUSTON LEE BROWN, a citizen of the United States, residing at St. Paul, in the county of Wise and State of Virginia, have invented a new and useful Cloth-Measuring Machine, of which the following is a specification.

The present invention relates to a machine for winding up and measuring cloth or lengths of other flexible material, and aims to provide a novel and improved appliance of that character for holding a bolt of cloth, measuring the cloth unwound from the bolt, and winding the same up.

Another object of the invention is the provision of a novel and improved registering mechanism for indicating the length of cloth wound up.

A still further object of the invention is the provision of a novel winding device for use in invoicing or taking inventory.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in the accompanying drawings, wherein—

Fig. 1 is a plan view of the machine.

Fig. 2 is a side elevation thereof.

Fig. 3 is a perspective of the winding reel.

Fig. 4 is a view of the invoicing device.

Fig. 5 is another view thereof looking at right angles to the line of view in Fig. 4.

Fig. 6 is an elevation of the register, the casing being shown in section.

Fig. 7 is a plan view of said register, portions being shown in section.

Fig. 8 is a detail view of the register mechanism.

Fig. 9 is a perspective view of a portion of one end of the reel and showing the crossed members separated.

Fig. 10 is an elevation of the lower portion of one of the standards, that portion of the base engaged thereby being shown in section.

The machine embodies a suitable base 1 adapted to be set on the floor, counter or other support, and carrying at one end a transverse basket or concaved receptacle 2

for holding the bolt 3 of cloth from which the material is to be taken. An inclined frame 4 carried by the base supports a transverse roller 5 over the basket or receptacle 2, 60 for the passage of the cloth 6 upwardly from the bolt 3 over said roller 5 to a transverse measuring wheel 7 whose shaft 8 is journaled in standards 9 carried by the base. The longitudinal bars of the wheel 7 are 65 provided with rubber teeth or spurs 10 for the engagement of the cloth, to assure of the the movement of said wheel by the cloth which passes over the wheel. Arms 11 pivoted to the frame 4 carry a pressure roller 12 70 which bears on the cloth, between the roller 5 and wheel 7, thus holding the cloth under tension, and causing it to bear on the wheel 7 with sufficient tension.

The transverse reel 13 is employed at said 75 end of the machine opposite to the receptacle 3, for winding up the cloth, and this reel is carried by a shaft 14, one terminal of which is inserted in an aperture in a revoluble standard 15 carried by the base. The other end of the shaft 14 is of square or non-circular form, as at 16, to fit in a corresponding socket 17 carried by the crank 18 journaled in a resilient standard 19 mounted on the base opposite to the standard 15. A bowed spring 20 is located at the opposite end of the reel 13 to bear against the reel for the purpose hereinafter pointed out. To remove the reel, the standard 19, which has a handle 19', is sprung laterally so that the socket 17, 90 is moved away from shaft 14. Standard 15 is then rotated and the shaft 14 can then be withdrawn from said standard 15.

In order to attach the end of the cloth to the reel 13, spring clasps 21 are carried by 95 one longitudinal bar of the reel, said clasps being of ordinary construction, and comprising pivotally connected jaws, one jaw of each clasp being fastened to the reel. A longitudinal shaft 22 is carried by the reel 100 adjacent to the clasps, and has fingers 23 to engage the loose jaws of the clasps for opening them to receive the cloth. The shaft 22 has a handle 24 at one end for turning it, and has a ratchet wheel 25 near said end to be engaged by a pawl 26 carried by the reel, whereby to hold the clasps open. By releasing the pawl 26, this releases the clasps which will close on the end of the cloth to carry it with the reel.

The standards 15 and 19 of the winding device are carried by a loose leaf 27 of the

base, hinged, as at 28. Thus, when the cloth is applied to the machine with its end placed on the uppermost part of the wheel 7, the leaf 27 can be raised to move the reel 13 adjacent to the upper portion of the wheel 7, bringing the clasps 21 in position to receive the end of the cloth. Then, by swinging the leaf 27 back into place, the cloth is moved over the wheel 7, thus starting the rotation thereof, after which, the leaf 27 being in place, the reel 13 is rotated by hand for winding the cloth thereon.

For use in invoicing or when taking inventory, there is used a holder 29 for the card or board 30 for rebolting the cloth. This holder 29 comprises the bars 31 hinged at one end, as at 32, to a block 33 having a trunnion 34 to be inserted into the standard 15 after the reel 13 and its shaft 14 have been removed. The free ends of the bars 31 are tapered or beveled, as at 35, to be received by the tapered slot 36 of a block 37 having a non-circular stem or shank 38 to fit into the socket 17 of the crank. A set screw 39 is carried by the block 37 to clamp the free ends of the bars 31 therein. When the bars 31 are detached from the block 37, they can be swung apart to receive the board 30, and then by swinging said bars together, they clamp the board therebetween, and said bars are held together by fitting the beveled ends thereof in the slot 36 of the block 37, and tightening the set screw 39. Then, when the crank is rotated, it will rotate the board 30 to wind the cloth thereon to rebolt the same, and obtain the linear measurement of the cloth. When the bars 31 are held by the block or clamp 37, they cannot swing relatively to the block 33, since relative longitudinal movement between the bars 31 is prevented. After the cloth has been wound on the board 30, the rebolting or invoicing device can be removed, and the board 30, with the cloth wound thereon is slipped off of the bars 31, leaving the bars and block 37 intact. The spring 20 holds the members 13' of the reel together. These members are notched where they cross at one end of the reel, (see Fig. 9) and normally interfit. When the desired amount of cloth is wound on the reel, the outer member 13' is pressed out against the spring and then turned so as to lie parallel with the other member 13' of the reel. Thus the cloth will collapse into a fold as though hanging on a line.

Coming to the registering mechanism, the same embodies a casing 40 mounted on the base, and spools or drums 41 and 42 are mounted for rotation therein and having a ribbon or tape 43 thereon suitably graduated, there being an aperture or opening 44 in the casing 40 to expose the graduations of the tape in succession, for indicating the length of cloth which has passed over the

measuring wheel 7. Each of the drums 41 and 42 is spring pressed, said drums having the respective spiral springs 45 and 46 therein tending to rotate each of said drums to wind the tape thereon, but the spring 45 is of greater tension than the spring 46 so that when the mechanism is released, the tape will be wound on the drum 41. The ratchet wheel 47 is carried by the drum 42 for the engagement of the pawl 48 to hold the tape 43 wound upon said drum, and the plunger 49 is slidable through the casing to be pressed by the finger for releasing the pawl 48 from the ratchet wheel, thereby permitting the drum 41 to wind the tape thereon to clear the register. One edge of the tape 43 is provided with teeth 50 for advancing the tape as the measuring wheel 7 is rotated.

The register advancing means includes members 51 carried by that standard 9 adjacent to the register, and leaf springs 52 terminally secured to said members and carrying between their ends, a block 53 through which a lever 54 extends and is pivoted, as at 55. A stop 56 is carried by the standard 9 for the contact of one arm of the lever 54, which is provided with a notch 57 normally moved away from the stop 56, thus preventing the movement of the lever 54 counter clockwise, as seen in Fig. 7, unless the lever 54 is shifted to bring the notch 57 into line with the stop 56. Said arm of the lever 54 has a pointed end 58 to engage the teeth 50 of the tape 43. The other arm of the lever 54 is provided at its end with a cam 59 lying in the path of movement of the respective spokes of the wheel 7, and there is a lug 60 at the end of the cam 59. Thus, as each spoke of the wheel 7 moves adjacent to the lever 54, it contacts with the cam 59, thereby sliding the lever 54 outwardly longitudinally thereof, due to the cam action, the springs 52 being caused to bow outwardly. This brings the notch 57 into line with the stop 56, and the spoke in engaging the lug 60 will therefore swing the cam end 59 of the lever 54 counter clockwise, as seen in Fig. 7. This movement of the lever 54, in the direction of the arrow 61, will first bring the pointed end 58 into engagement with the teeth 50 of the tape, and the pointed end 58 is then moved toward the right, as seen in Fig. 7, to advance the tape one step. After the spoke has passed the lug 60, the spring 52 will retract the lever from the tape, and the pawl 48 in engaging the ratchet wheel 47, will hold the tape wound on the drum 42. This tape is of steel or other suitable metal, whereby it will be advanced by the lever 54 against the tension of the spring 45, the spring 46 serving to wind the slackened portion of the tape onto the drum 42. Thus, as the cloth passes over the measuring wheel 7, the tape 43 is advanced step by

step, and by observing the graduations on the tape through the opening 44, the operator can note the amount of material wound up. When the desired amount of material 5 has been wound up, the material can be cut in two at the top of the measuring wheel by a shears, knife or other suitable implement. To clear the register, the plunger 49 is pushed, thereby releasing the pawl 48, and 10 permitting the spring 45 to wind the tape back onto the drum 41. The tape 43 is advanced one step by the engagement of each spoke of the wheel 7 with the lever 54, and the graduations on the tape correspond to 15 the spacing of the spokes of the measuring wheel at the periphery thereof, as will be apparent.

Having thus described the invention, what is claimed is:—

- 20 1. A cloth measuring machine including a hollow container for a bolt of cloth, a measuring wheel having longitudinal bars, flexible cloth engaging teeth outstanding from the bars, a winding reel, a roller for 25 supporting cloth passing from the receptacle or container, and a pressure roller for bearing on the cloth between the supporting roller and the wheel.
2. A cloth measuring machine embodying 30 a base having a hinged leaf, a measuring wheel carried by the base, and winding means carried by said leaf to be swung adjacent to the measuring wheel for the attachment of the end of the cloth.
- 35 3. In a cloth measuring machine a base, a revolute standard mounted on the base, a second standard adapted to flex laterally, a shaft supported by one standard, an actuating crank journaled in the other standard 40 and detachably engaging one end of the shaft, and a reel upon the shaft.
4. In a cloth measuring machine, a rebolting device embodying a holder comprising a block, a pair of bars each hinged independently at one end to said block, the other ends 45 of the bars being beveled, a second block having a tapered slot to receive said beveled ends of the bars, means carried by the second mentioned block for clamping the bars there-
- in, and means for mounting the said blocks 50 for rotation.
5. A measuring machine embodying a measuring wheel, a register, a lever normally disengaged from the register, means for preventing the lever from swinging until moved 55 into engagement with the register, and said lever having means whereby the wheel in engaging the lever first moves the lever into engagement with the register and then swings the lever to advance the register. 60
6. A measuring machine embodying a measuring wheel, a register, a register advancing lever, means for mounting said lever for longitudinal and swinging movements and for normally retracting the lever from 65 the register by longitudinal movement of said lever, and means to prevent the lever from swinging to advance the register until the lever is moved longitudinally into engagement with the register, the lever having 70 a cam for the engagement by portions of said wheel, to move the lever longitudinally into engagement with the register and having means for swinging the lever by said portions of the wheel after the lever is moved 75 into engagement with the register.
7. A measuring machine embodying a measuring wheel, a pair of drums, a graduated tape carried by said drums to be wound thereon, a spring for normally winding the tape on one drum, a spring weaker than said spring for winding the tape on the other drum, means for preventing the unwinding of the tape from the second mentioned drum, releasable to bring the first 80 mentioned spring into action for winding the tape on the first mentioned drum and the tape having teeth, and advancing means operated by the wheel for movement into engagement with said teeth to advance the 85 tape.

In testimony that I claim the foregoing as my own, I have hereto affixed my signature in the presence of two witnesses.

HOUSTON LEE BROWN.
